UNITED STATES PATENT OFFICE.

WILLIAM EDWARD MOSS, OF LISCARD, ENGLAND.

LAUNCHING OF SHIPS' BOATS.

1,304,353.

Specification of Letters Patent.

Patented May 20, 1919.

Application filed February 12, 1919. Serial No. 276,493.

To all whom it may concern:

Be it known that I, WILLIAM EDWARD Moss, a subject of the King of Great Britain, and a resident of Liscard, Cheshire, England, have invented certain new and useful Improvements Relating to the Launching of Ships' Boats, of which the following is a specification.

In launching ships' boats in the usual way by means of pulley blocks and rope falls it frequently occurs owing to the separate control of the falls, and by reason of the ropes jamming in the pulleys or one operator paying out faster than the other, that one end 10 of the boat is held up while the other end continues to fall, the boat then taking a dangerous inclination and the occupants being frequently thrown into the sea. The object of the present invention is to provide 15 means, whereby the boat can only be lowered from the falls on a comparatively even keel, even though they be independently operated, any inclination of the boat beyond some predetermined angular limit causing a brake to 20 come into action on the falls at that end of the boat which is being lowered relatively faster than the other end, the brake automatically releasing itself when the boat comes again to an even keel.

According to this invention the lower pulley blocks of a ship's boat launching system are provided with a brake mechanism such that the brake operates on the fall ropes or the pulleys, at that end of the boat which 25 is descending lower, by the pivotal action of the boat about its point of suspension from the pulley block. This may be effected for instance by a weighted brake mechanism which would be free of the falls while the 30 boat was horizontal or substantially so but would be operated by an inclination of the boat, or by providing the lower block with a brake mechanism which is thus adapted to be brought into action by the engagement of 35 an element carried from the boat at a point beyond the point of its suspension from the lower pulley block, both lower pulley blocks of the falls being similarly fitted. With such an arrangement should one end of the 40 boat in launching fall below the other some predetermined distance, the element carried from the then lower end of the boat would actuate its brake mechanism and prevent any further lowering of that end, the brake 45 being, however, released by the reverse pivotal action of the boat about its point of sus-

pension at the lower end as the falls continue to be paid out at the higher end, and as the boat again assumed a horizontal position.

The invention is illustrated in the accompanying drawings, in which Figure 1. shows the brake mechanism applied to the lower blocks of the falls of a ship's boat launching gear, the brakes being in the off or inoperative position, Fig. 2. being a fragmentary view of one end of the boat showing the brake mechanism in action.

In carrying out the invention the brake mechanism consists of one or more shoes 1 pivotally connected at 2 to one end of a lever 3 which is itself pivoted at 4 on the lower pulley block 5. The other tail end 6 of the lever 3 is adapted to be engaged and operated by the eye 7 of a rod 8 or other element rigidly carried from the boat 9 at a point outside or nearer the end 10 of the boat than the point of suspension 11 of the boat from the lower block, this point of suspension being the lower part of the usual ring 12 on the lower block 5, and engaged by the hooks 13 of the boat 9. The tails 6 of the brake levers are relatively reversed as shown and extend toward the ends of the boat in each case, and the elements 8 carried from the boat which put the brake mechanism in operation embrace the free ends 6 of the levers. The brake lever in its normal inoperative position being horizontal and parallel to the boat, supposing one end of the boat to be lowered faster than, and to fall relatively to, the other end, a pivotal action of the boat about its point of suspension 11 at the higher say the left hand end takes place, but there is also a corresponding pivotal action about the other right hand point of suspension 11 at the lower end, and this results in the part of the boat beyond such lower point of suspension inclining still lower than the point of suspension at that end. Consequently the eye element 7 or the like carried on the outer end of the boat and engaging the lower 6 is depressed relatively to the lever and by engaging therewith rotates the lever and forces the brake shoes 1 into contact with the rope falls 14, as shown dotted Fig. 1. or in full lines Fig. 2. where they encircle the lower half of the pulleys 15, and thus arrests further travel of such ropes. The falls at the lower end of the boat are thus braked, and effectively prevent any further lower-

ing of that end until the boat is righted to a horizontal or approximately horizontal position, the brake mechanism then becoming free again, owing to the reversed pivotal 5 action of the boat about this point of suspension 11. Similarly, if the other or left hand end of the boat falls below the level or some limiting angle, the brake mechanism on that side comes into action.

10 The tails 6 of the brake levers are shown turned up at 6^a, this construction insuring that the brake shall be brought into action, much sooner than if the tails of the levers were straight; and if it be desired that the 15 brake action shall not be so sensitive, that is to say, that the boat shall be permitted to dip at either end to a greater angle of inclination say 10 degrees, or more from the horizontal before the brake comes into action, the ends 6^a of the lever would not be turned up so sharply as shown in the drawings, or they might even be made straight.

If desired additional means may be provided for actuating the brake mechanism 25 by hand, and by adjusting or shaping the engaging surfaces of the lever tail 6^a and the eye element 7 carried from the boat, the action of the brake may be arranged to take place when the angular inclination of the 30 boat from the horizontal has reached any predetermined amount.

Where the lower blocks of the boat falls are connected by a bar or the like for the purpose of preventing twisting of the falls, 35 the brake mechanism may be arranged to be actuated from, and by tilting of, the connecting bar or the like.

I claim.

1. A brake mechanism for controlling the 40 launching of a ship's boat on an even keel, comprising, fall ropes, a pulley around which the fall ropes pass, a brake mechanism adapted to retard the passage of the ropes around the pulley, and means for controlling the brake mechanism operated by the pivotal action of the boat when inclining about its point of suspension from the fall ropes.

2. A brake mechanism for controlling the 50 launching of a ship's boat on an even keel, comprising, fall ropes, a pulley around which the fall ropes pass, a brake mechanism adapted to engage the fall ropes where they pass around the pulley, and means for controlling the brake mechanism operated by the pivotal action of the boat when inclining about its point of suspension from the fall ropes.

3. A brake mechanism for controlling the 60 launching of a ship's boat on an even keel,

comprising, fall ropes at each end of the boat, upper and lower pulley blocks around which the fall ropes pass, a separate brake mechanism for the falls at each end of the boat, and means for controlling the brake 65 mechanism operated by the pivotal action of the boat when inclining about its point of suspension from the fall ropes.

4. A brake mechanism for controlling the launching of a ship's boat on an even keel, 70 comprising, fall ropes at each end of the boat, upper and lower pulley blocks around which the fall ropes pass, a separate brake mechanism engaging the falls where they pass around each of the lower pulley blocks, 75 and means for controlling the brake mechanism operated by the pivotal action of the boat when inclining about its point of suspension from the fall ropes.

5. A brake mechanism for controlling the 80 launching of a ship's boat on an even keel, comprising, fall ropes at each end of the boat, upper and lower pulley blocks around which the fall ropes pass, brake levers pivoted on each lower pulley block, brake shoes 85 carried by the levers and engaging the fall ropes passing around the pulleys, elements carried from the boat at points nearer its ends than the points of suspension of the boat from the lower pulley blocks, said elements 90 engaging the levers, whereby when one end of the boat is descending lower than the other the brake lever at that end is actuated by the pivotal movement of the boat about its point of suspension from the lower 95 pulley blocks.

6. A brake mechanism for controlling the launching of a ship's boat on an even keel, 100 comprising, fall ropes at each end of the boat, upper and lower pulley blocks around which the fall ropes pass, brake levers pivoted on each lower pulley block, turned up ends on the levers, brake shoes carried by the levers and engaging the fall ropes passing around the pulleys, elements carried 105 from the boat at points nearer its ends than the points of suspension of the boat from the lower pulley blocks, said elements engaging the turned up ends of the levers, whereby when one end of the boat is descending lower than the other the brake lever at that end is actuated by the pivotal movement of the boat about its point of suspension from the lower pulley blocks.

In testimony whereof I affix my signature 115 in presence of two witnesses.

WILLIAM EDWARD MOSS.
